UNITED STATES PATENT OFFICE.

PHELPS BROWN AND HAROLD H. CLARK, OF SPRINGFIELD, MASSACHUSETTS; SAID CLARK ASSIGNOR TO WICO ELECTRIC COMPANY, OF SPRINGFIELD, MASSACHUSETTS, A CORPORATION OF MASSACHUSETTS.

MAGNETO.

Application filed June 25, 1921. Serial No. 480,348.

To all whom it may concern:

Be it known that we, PHELPS BROWN and HAROLD H. CLARK, citizens of the United States, residing at Springfield, in the county of Hampden and State of Massachusetts, have invented new and useful Improvements in Magnetos, of which the following is a specification.

This invention relates to improvements in magnetos and is especially directed to magnetos of the type wherein a reciprocating armature moves into and out of engagement with magnetic poles to vary the flux in a magnetic circuit and by such variations to cause the generation of electricity in a suitable winding.

The invention is particularly concerned with mechanism for actuating the armature in a novel manner. Heretofore, it has been thought essential, in magnetos of the type described, to apply to the armature very suddenly, if not practically instantaneously, a relatively high initial force to dislodge the armature from its poles and overcome the opposing force due to magnetic attraction. Hence, the use of the hammer which, when suddenly released, is driven toward the armature and, after acquiring considerable momentum, engages the latter with an impact which sets the armature suddenly in motion at high speed. Such actuation of the armature was considered necessary in order to provide for a rapid change in flux in the generating windings. Other prior art magnetos, of the type under consideration, while dispensing with the hammer, have nevertheless retained the sudden and practically instantaneous release of the armature to allow the sudden application of a considerable initial driving force.

This invention is concerned, broadly, with improvements in magnetos of the type in which an armature is moved into and out of contact with magnetic poles and a driving mechanism is provided to build up on the armature, while held to its poles, a differential of force to disengage it therefrom. This differential, by reason of its infinitesimal initial value, is not capable of moving the armature away from its poles at high speed, but, as soon as the least air gap is established between the armature and its poles, the differential is increased considerably and continues to increase very rapidly until

within a very short time it becomes effective to rapidly move the armature. This increase in the differential is due to the rapid weakening of the resistance to armature movement, which resistance includes as a principal element the force of magnetic attraction.

This invention has for an object to provide a magneto, of the general type defined, in which the armature flight is effected in the above manner and the armature, once it is deposited on the cores, is held thereto by magnetic attraction, the force of the latter being then superior to that of the driving means by which it is subsequently moved in the other direction, together with means periodically operable to progressively oppose the force of magnetic attraction until the driving means becomes effective to move the armature.

According to this feature of the invention, the armature may be deposited on its cores by any suitable mechanism, which, once it has deposited the armature, may then withdraw, leaving the armature held in place by magnetic attraction. This condition will then continue until the magnetic hold on the armature is broken, after which the driving means, being now superior to the weakened force of magnetic attraction, will drive the armature away from the cores at rapidly increasing speed in the manner above outlined.

An important advantage results from this mode of operation due to the lessening of the force of the driving means, usually a spring, the maximum tension of which is less than the maximum force exerted on the armature. This diminution in the strength of the drive spring means that less force is required to oppose it and a reduction in this force means a lessening of the wear on the parts.

Another important advantage of this mode of operation is that the mechanism used to deposit the cores on its poles may be relatively slow acting in withdrawing from its poles—that is, it need not withdraw practically instantaneously, as has heretofore been common, for the armature, being held to its poles independently of such mechanism, can dwell in such position until the relatively slow acting mechanism has had time to get out of the way, in so far

as interference or obstruction to the high speed movement of the armature is concerned. Thus, the reciprocating mechanism of the magneto may be chosen with a view to its quietness in operation. The usual arrangement of a cam, which periodically releases its follower for a free and practically instantaneous fall, is no longer necessary and much less violent motions may successfully be used, retaining the substantial advantages of the reciprocating armature type of magnetos without the usual disadvantages of undesirable noise and rapid wear of parts.

Another object of the invention is to provide an actuating mechanism for the armature, whereby, when the armature is seated on its poles, the armature driving spring is under no tension, or substantially none, and whereby, previous to the breaking of the magnetic hold on the armature the driving spring is placed under the desired tension.

Another object of the invention is to provide, in a magneto of the type set forth, adjustable means for breaking the magnetic hold on the armature, or "tripping" it, at various times after its deposit on the cores, whereby variations in timing of the currents generated may be effected by varying the time when the armature is released for its flight away from the poles.

According to this feature of the invention, the "tripping" means may be made independent of the mechanism for depositing the armature on its poles and this is important, for variations in timing may be effected without changing the timing of the armature-depositing mechanism.

Another object of the invention is to connect the tripping mechanism for actuation by the depositing mechanism for the purpose of avoiding unnecessary multiplication of parts.

Other objects of the invention relate to improvements in the construction and arrangement of parts and will appear in the following description and in the illustrative embodiment of the invention in the accompanying drawings, in which,—

Fig. 1 is a fragmentary elevational view showing the mounting of the magneto on an engine;

Fig. 2 is an enlarged front elevational view of the magneto with the casings removed to show the interior;

Fig. 3 is a cross-sectional view of the magneto;

Fig. 4 is a bottom plan view of the magneto with the armature and associated moving parts removed;

Fig. 5 is a diagrammatical view of the electrical connections of the magneto;

Figs. 6, 7, 8, and 9 are diagrammatical views illustrative of successive steps in the operation of the breaker-points, which control the opening and closing of the choke-coil circuit;

Figs. 6^a, 7^a, 8^a, and 9^a are diagrammatical views showing the relative positions of the armature and poles which obtain when the breaker-points are in the respective positions shown in Figs. 6, 7, 8, and 9;

Fig. 10 is a top plan view of a part of the interrupter-actuating mechanism;

Fig. 11 is a view, taken similarly to Fig. 3, showing modifications in certain parts of the magneto; and

Fig. 12 is a top plan view showing a modification of the structure shown in Fig. 10.

In these drawings, there is shown, in full detail, an embodiment of the invention incorporating many desirable features relating to the particular construction and arrangement of various parts, which, although important and preferred, are not essential as far as the broader aspects of the invention, heretofore outlined, are concerned. As to each of the latter, the showing is to be taken merely as an illustrative example of one of many suitable types of magnetos, in which they may be embodied.

The magneto includes a group of stationary parts, such as the magnetic source, cores, and coils, which may be supported in any suitable manner, as by a bracket *a*, from the engine frame, as *b*, and a second group of movable parts, such as the armature and associated mechanism, which may be actuated from the engine by various means. One illustrative example of such means is shown in Fig. 1. Thus, the crank-shaft of the engine, indicated at *c*, drives the cam-shaft *d*, as by gearing *e*, at the desired ratio of speed. The cam-shaft *d* has mounted thereon a cam *f*, which in this particular instance is shown as an eccentric, as an example of the most quiet and most smoothly acting cam that is available. While other types of cams, or actuating means other than cams, may be used, the eccentric is preferred for its relative quietness and smoothness in operation. With the use of an eccentric the direction of rotation of the cam-shaft becomes immaterial.

The stationary group of parts includes a back frame 15, from which all the other parts of this group are supported. This member 15, which is of non-magnetic material, is provided with tapped holes 16 to permit its attachment to the bracket *a* described and also with a forwardly-extending boss 17. Mounted in and secured to the latter, as by the screw 18, is a rod 19, which extends downwardly below the lower edge of the frame and forms a guide for the moving parts of the magneto.

The source of magnetic flux, in this particular instance, comprises a series of permanent bar-magnets 20 arranged in superposed relation and grouped into a unit for con-

venient assembly in the general manner disclosed in U. S. Letters Patent No. 1,335,119 granted March 30, 1920, on an invention of T. G. Louis. That is, the ends of like polarity of all magnets are received within substantially U-shaped clips 21, to which they are firmly held, as by shims or wedges 22. The clips 21, although of magnetic material, are not hard, as are the magnets 20, and are 10 readily drilled to receive the attaching devices, later to be described. Various other means may be employed for securing the magnets in place and the clips are given merely as an illustration of one of many 15 suitable means.

A magnetic pole-piece is provided for each pole of the magnetic source and each of these pole-pieces is made up of two rectangular blocks 23 and 24. The two blocks for each 20 pole piece, as shown in Fig. 3, are arranged side by side and are recessed to receive between them the upper end of a core 25. The latter, as indicated in Fig. 4, is built up of laminations which are drawn together by, 25 and held to, the mating pair of blocks by a single screw 26 (Fig. 3). The latter passes through the back frame 15, through the block 24 and core 25 and threads into the block 23. The screw 26 serves to draw the 30 blocks together, thereby clamping the laminations of core 25 and also securing these parts to the back frame 15. The clips 21, above described, are secured to their respective pole-pieces by screws 27 which pass upwardly through the latter and thread into the lower part of the clips, there being two screws for each clip, as indicated in Fig. 3. The two pole-pieces may be further tied together by a bar 28, of non-magnetic material, 40 which connects the spaced blocks 23 and is secured thereto by screws 29.

The two cores 25 extend downwardly from their pole-pieces in parallel relation, one on each side of the guide-rod 19, and 45 terminate at a short distance below the lower edge of frame 15. Near their lower ends, the laminations of the cores are clamped together and connected to the frame 15 in a manner similar to that above described except that two members 30 and 31, of non-magnetic material, suffice for both cores. Two screws 32, passing through frame 15, member 30 and the cores 25, 50 thread into member 31 and serve to draw the members together and hold them to the frame.

Upon each core 25, and between the points at which it is clamped, are provided two coils 33 and 34 arranged one upon the other. The 60 inner coils 33 are provided for a choking function, either to retard the building up, or the diminution of, magnetic flux in cores 25. The outer coils 34 constitute the generating winding. The electrical connections of these coils are shown in Fig. 5. The coils

34 are usually, although not necessarily, connected in series, as by a wire 35 joining one terminal of each coil. The other terminals of generating winding, constituted by the connected coils, are the service terminals. Customarily, one terminal is grounded, as by a wire 36, to the frame of the magneto and the other extends to the ignition system, as indicated by the wire 37 extending to a spark-plug 8.

The two coils 33 are also usually, although not necessarily, connected in series, as by a wire 38 joining one terminal of each coil. The other terminals of the choke-winding, afforded by the connected coils 34, are connected to relatively-movable breaker-points 39 and 40 and a condenser 41 is bridged across these terminals in the usual manner. Usually, as shown, one terminal of one coil 33 is grounded, as by a wire 42, to the frame of the machine, whereby to conveniently connect with the movable breaker-point 40, which, as will appear, is in constant metallic connection with the frame, and one side of the condenser 41 is similarly 90 grounded. The corresponding terminal of the other coil 33 is connected, as by a wire 43, to the stationary breaker-point 39 and the other side of the condenser 41. The latter is conveniently located beneath the magnets 20 and between the clips 21, where it is supported by resting upon the blocks 23 and 24 (Figs. 2 and 3).

The magnetic circuit will be readily understood from Fig. 5. The poles of the 100 magnetic source, extended by the cores 25 to admit the windings 33 and 34 are periodically connected and disconnected by an armature 45, thereby providing for a magnetic circuit of alternately low and high 105 reluctance through the windings.

The armature 45, as best shown in Fig. 3, may be made up of laminations in the usual manner, although this is not necessarily 110 essential. The armature is fixed to a guide sleeve 46 and the laminations are spread apart at the center of the armature to permit the sleeve to pass therethrough. Bolts 47 (Fig. 2) located on opposite sides of sleeve 46, pass through the armature and serve to 115 clamp the laminations thereof together as well as to bind them to the sleeve. Slidable within sleeve 46, and upon the guide-rod 19, is a second sleeve 48 upon the lower end of which is threaded a collar 49 and below the latter a fork 50. The eccentric 5 is provided with a suitable strap 51 to which is fixed a stud 52 and adjustably threaded on stud 52, and held in its various 120 positions thereon by a lock-nut 53, is a member 54 which fits within fork 50 and is pivotally connected thereto by a pin 55. Both sleeves 46 and 48 have longitudinal slots 56 and 57 respectively, extending from their upper ends downwardly a substantial dis- 130

tance. These slots function as keyways, both being arranged to cooperate with a single key 58 in rod 19, which key permits the desired vertical sliding movements of the sleeves and yet holds them in the desired angular relation. More particularly, it keeps the armature 45 properly positioned with respect to cores 25.

Preferably, although not necessarily according to all features of the invention, the armature 45 is not lifted directly by the cam-follower or lifting sleeve 48 but rather through the intermediary of resilient means. As shown, such means consist of a coil-spring 59 which acts between the collar 49 and the flanged lower end of the sleeve 46.

For the purpose of moving the armature rapidly away from its poles, a driving-spring 60 is provided and the force exerted by this spring on the armature, when the latter is positioned as in Fig. 3, is less than the force of magnetic attraction on the armature, and as will later appear may be at such time reduced to, or substantially to zero. The spring 60, as shown, is a coil spring which encircles the sleeves 46 and 48 and acts between a spring-seat 61, which abuts the lower face of the boss 17 on frame 15, and a cup-shaped spring-seat 62 which slips over sleeve 46 and acts against the upper face of armature 45. As shown, a plate 63, also loosely fitting on sleeve 46, is interposed between seat 62 and the armature and projects laterally therefrom for connection to the interrupter mechanism to be later described. As shown in Fig. 4, the members 30 and 31 are recessed centrally at 64 to receive and closely fit the peripheral wall of the cup-shaped spring-seat 62, and such wall is of sufficient longitudinal extent so that its open upper end never passes out of the lower end of opening 64, thus preventing the ingress of dust and dirt into the magneto through the bottom closure afforded by the members 30 and 31.

The interrupter includes a cylindrical casing 65, which is driven into an opening in the member 31 and thereby held stationarily to the frame structure already described. This casing extends upwardly in parallelism with the line of travel of the armature and is located at the front of the magneto for convenient access and inspection. At the upper end of the casing 65 is a bridge 66 in which the stationary breaker-point 39 is adjustably mounted and from which it is suitably insulated, all as indicated in Fig. 3. The movable breaker-point 40 is carried on the upper end of a relatively long cylinder 67 which closely fits in and is guided by the casing 65. The lower end of cylinder 67 is closed, except for a central opening to receive a rod 68 which passes loosely therethrough and into the casing. The upper end of rod 68 carries a head 69 and between

this head and the closed upper end of casing 67 is a spring 70, through the intermediary of which the cylinder 67 is lifted from the rod 68. The latter, in its descending movement, lowers cylinder 67 by reason of the abutment of head 69 with closed lower end of the cylinder. The lower end of rod 68 is threaded into and thereby adjustably secured to, the projecting portion of the plate 63 above described. A screw-driver slot is provided in the lower end of rod 68, whereby it may be conveniently turned for adjustment and a lock-nut 71 is provided on the rod to prevent change of the adjustment.

It is to be noted that the movable breaker-point 40 can yield relatively to its actuating rod 68. Such yield is desirable for several reasons. First, the travel of rod 68 need not be the same as the travel of point 40. Second, it is desirable that the latter be less than that of rod 68 to compress the spring 70 after engagement of the points 39 and 40, so that the latter will be held firmly pressed together even after considerable wear. Third, it is desired, according to one feature of the invention, to be able to open the breaker-points after they have been closed by upward movement of the armature and while the latter is seated on its cores. For this purpose, a lever 72 is provided which is pivoted intermediate its ends at 73 to a bracket 74 fixed to boss 17 by the screw 18 described. Lever 72 may consist simply of a member bent into the shape of a hairpin (Fig. 10) and passed through a block 75 of fibre below the pivot-pin 73, by means of which the block is supported in the forked lower end of bracket 74. The curved end of lever 72 lies in the path of the cylinder 67 of the interrupter mechanism and the other, and laterally-spaced, ends straddle guide-rod 19 and lie in the path of the upper end of sleeve 48. This sleeve has a greater travel than the armature and, after the latter has been seated, continues to move upwardly and in such movement engages and lifts the inner end of lever 72, thereby depressing its outer end and lowering cylinder 67 with the breaker-point 40 carried thereby. On a reverse movement the sleeve 48 moves downwardly sufficiently to release lever 72 and allow the breaker-points to close previous to disengagement of the armature from its poles.

Another advantageous way of constructing the lever 72 is shown in Fig. 12, the difference being that instead of a single hairpin shaped member, as shown in Fig. 10, two straight members 72' are passed through block 75 in converging relation, the converging ends lying at the sides of the breaker point 40 rather than at the back thereof. With this arrangement, the casing 65 of the interrupter mechanism is turned 90° from the position illustrated in Fig. 3.

The means for breaking the magnetic hold upon armature 45, or, as it may be termed, tripping it so as to allow spring 60 to act and drive it rapidly downward, may be variously constructed as desired, although, of course, it will be controlled from the moving parts of the engine, as from the cam-shaft *d* for example. For the purpose of avoiding unnecessary multiplication of parts, we prefer to control and actuate the tripping means from the mechanism by which the armature is deposited on the cores 25.

This result may be accomplished in the following simple manner. A collar 76 is slipped over sleeve 46 prior to assembly of the armature thereon and is held between the latter and the flanged end of sleeve 46. This collar 76, as shown, is cupped downwardly and then bent outwardly to afford a circular flange 77, which is spaced from the armature. A second collar 78 is adjustably connected to the collar 49, as by the screw-thread connection shown, and extends upwardly therefrom, terminating with a circular flange 79 above, but located in the path of flange 77. Thus, after the sleeve 48 has descended a predetermined distance, which may be varied by turning collar 78, the

flanges 79 and 77 will be engaged and armature 45 will be pulled away from its poles, breaking the magnetic hold on the armature and allowing spring 60 to drive it rapidly downward. It is also to be noted that these members 76 and 78 constitute telescoping housings for spring 59 to conceal and protect the latter and prevent to a considerable degree the ingress of dust and dirt.

Another way of tripping the armature is shown in Fig. 11. In the arrangement there shown, the guide rod 19 has been replaced by a guide sleeve 19', and a lifting rod 48' rather than a lifting sleeve, slides inside of it. The guide sleeve is slotted longitudinally at opposite points in its peripheral wall, as indicated at 81 and a pin 82, driven through the lifting rod 48', has projecting end portions which ride in these slots and extend beyond the guide sleeve 19'. Loosely mounted on the latter beneath pin 82 is a cupped washer 83 which forms a seat for the drive spring 60. The latter, as shown, is fully expanded and under no stress but is adapted to be compressed, and thus stressed, by the descent of the rod 48'. After the latter has moved downwardly sufficiently to place spring 60 under the desired stress, washer 83 abuts the upper end of the armature sleeve 46 and pulls the armature 45 away from its cores, allowing the spring, previously stressed as described, to drive the armature rapidly downward.

In connection with this tripping arrangement, means are provided for varying the time in the stroke of member 48' at which

the abutment forming washer 83 will engage sleeve 46. This means consists of an eccentric connection between fork 50 and member 54 whereby the sleeve 46 may be drawn toward or moved away from the eccentric strap 51. Thus, in place of the pivot pin 55, heretofore described, a pin is provided having concentric end portions 85 mounted to turn in the arms of fork 50 and an intermediate eccentric portion 86 to fit 75 into the eye in member 54. A handle 87 is fixed to one of the portions 85 for convenience in turning this pin and effecting the adjustment described. The eccentric 86 may be turned to move rod 48' upwardly a sufficient distance so that washer 81 cannot abut sleeve 46 at any point in its stroke. Thus, the armature 45 may remain on its poles during reciprocation of rod 48', whenever desired.

Various other means may be devised for tripping the armature in the manner described and the invention, in its broader aspects, is independent of the particular means described. The particular tripping means disclosed are, in a measure, preferred on account of their simplicity and convenient adjustability.

The magneto may be suitably encased, as indicated in Fig. 1, by housings 80 and 81 which enclose all parts above the members 30.

The operation of the magneto, and more especially the movements of the armature with which the broad features of the invention are concerned, will now be described. Assuming that the cam-follower sleeve 48 is in its lower position and that the eccentric *f* is rotating, the sleeve 48 will be raised progressively and relatively gradually to deposit the armature on its poles (comprising the lower ends of cores 25). The raising of the armature, however, is preferably not directly accomplished by sleeve 48, for it is usually desired to seat the armature on its poles as quietly as possible. Therefore, the cam follower transmits its lifting force to armature 45 through the intermediary of the spring 59. Opposing the action of the latter is the drive-spring 60, and the armature is thus carried upward between two forces, which naturally seek a balance. The upward movement of the armature is therefore not directly proportional to the movement of the cam-follower, for the latter encounters increasing resistance as it moves upwardly by the compression of spring 60, and as the latter compresses the spring 59 must compress to balance it. Therefore, the upward movement of the armature, which may be initially nearly as fast as the cam-follower, soon becomes slower and slower as it approaches the poles. This particular mode of lifting the armature, although 125 desirable and preferred because it permits

a gentle seating of the armature on its poles, is not essential to the broad features of the invention.

In the above description of the forces 5 acting on armature 45 during its upward travel, no consideration was given to the upward force which would normally tend to draw the armature to its poles with a sharp noise, for as the armature nears the latter 10 the magnetic pull would increase very rapidly, and this rapidly-increasing force added to that of spring 59 would tend to defeat the object sought for, viz, the depositing of the armature on the cores as quietly as possible. 15 However, the effect of magnetic pull is substantially reduced so as to be a practically negligible factor in the described operation. This is accomplished by the closing of the choke-coil circuit during the latter part of 20 the upward flight of the armature. The breaker-points, controlling the opening and closing of this choke-coil circuit, are, when the armature is in its lowest position (Fig. 6^a), open as shown in Fig. 6. As the armature nears its poles to a position such, for example, as is indicated in Fig. 7^a, it has 25 moved sufficiently to carry the breaker-point 40 into engagement with the fixed breaker-point 39, as indicated in Fig. 7, thus closing 30 the circuit in which the choke-coils are located. On continued movement of the armature, spring 70 compresses to take care of the over-travel of rod 68, and the points remain closed until after the armature has 35 been seated on its poles. These coils, when in a closed electrical circuit, oppose a change of flux in the magnetic circuit, and in this instance they oppose the building up of the flux in cores 25 and consequently there will 40 not be immediately a magnetic pull on the armature of anything like the usual strength. The force, due to magnetic pull, is substantially reduced over that which would otherwise exist if the choke-coil circuit 45 were left open.

After the armature has been seated on its poles, the cam-follower continues its upward travel, the spring 59 by its further compression, permitting this action. This 50 "overtravel" of the cam-follower is important since it insures that the armature will continue to be seated on its poles even after extended wear. It is also important as it affords a means for opening the breaker 55 points after the armature has come to rest on its poles and is no longer available to actuate them. Continued travel of the cam-follower opens the breaker-points as illustrated in Figs. 3 and 9, thus allowing the 60 flux to build up rapidly in the now closed magnetic circuit.

The cam-follower having reached the upper end of its stroke, will in the present case, immediately commence to descend but the 65 armature 45 will remain on its poles be-

cause the force of magnetic attraction acting on the armature is at that time superior to that of spring 60. The first result of the downward movement of the cam-follower is an expansion of spring 59 and a release of 70 lever 72, whereby the breaker-points are closed. The closing of the latter occurs before the engagement of the flanges 72 and 79 and thus before the armature leaves its poles. This condition is illustrated in Figs. 75 7 and 7^a. Thus, the choke-coils are again brought into play on the magnetic circuit, but for a different purpose, viz, to oppose any sudden change in magnetic flux when the armature leaves its poles. 80

The disengagement of the armature from its poles is not accomplished by the sudden application of a substantial initial force. On the contrary, when in the descent of the cam-follower, the force opposing the driving action of spring 60,—in this instance that due to magnetic attraction,—becomes slightly less than that of spring 60, the armature will begin to move but naturally slowly in its initial infinitesimal step of 85 downward movement because the driving force is infinitesimal. The lessening of the force of magnetic attraction is effected by bringing into play a force which supplements that of the drive-spring. That 90 is, the flange 79 will eventually engage flange 77 and a downward pull will be applied to the armature. This supplementary force is, however, applied progressively until the combined forces of spring 95 60 and the tripping mechanism just overbalance that due to magnetic attraction and supply a differential of force to move the armature. The supplementary force exerted by the tripping mechanism is, however, of very short duration and hence this mechanism has been said to "trip" the armature in order to allow the spring 60 to act. Practically, the instant the armature is separated from its poles by a very slight air 100 gap, the force of magnetic attraction has 105 been so very greatly diminished that spring 60 is then superior to it. Continued increase in the air gap diminishes the force exerted on the armature by magnetic attraction still more rapidly. On doubling the air gap, the force is at the very least quartered, and so on. Thus, once the armature is started from its poles, no matter how slowly, by the very smallest differential of 110 force, its subsequent movement is rapidly accelerated on account of the exceedingly rapid diminution of the resisting force. The practical result is that a high armature 115 speed is obtained after the armature has moved away from its poles a certain distance, and at the point of maximum speed, or as nearly thereto as it can be arranged, the breaker-points open. The choking effect 120 on the magnetic circuit having been 125

- thus done away with, there results a very rapid change of flux in this circuit, thereby inducing a high voltage in the generating winding. Thus, by the expedient of the 5 breaker points and choke-coil winding, which may be likened to a valve for controlling the flux in the magnetic circuit, it is possible to hold the flux in the latter until the armature gets under way and attains a 10 sufficient speed. Otherwise, the change in flux would be relatively gradual because it would depend entirely on the speed of the armature in the initial stages of its downward flight. 15 To complete the description of operation, it should be noted that the spring 59 has still another function which is to yieldingly and quietly arrest the armature in its downward flight. After the breaker-points have opened 20 for the purpose of releasing the flux in the magnetic circuit, the driving force of spring 60, by its expansion, weakens and in addition encounters increasing opposition by reason of spring 59 and the forces due to 25 these two elements seek and find their balance and thus arrest the armature in the desired quiet manner.
- The operation of the magneto shown in Fig. 11 is essentially like that already described. The springs 59 and 60, however, do not in this instance cooperate in the manner above-described but the armature 45 moves proportionately with the lifting rod 48' until it engages its poles. The cushioning effect, 30 above described, is not so essential to a gentle seating of the armature on its poles, where the force of magnetic attraction is, as here, substantially diminished. After the seating of the armature, the rod 48' continues its 35 upward movement, relaxes the tension of spring 60, entirely if desired, and later on its downward movement places this spring under stress and thereafter trips the armature. 40
- The cooperating flanges 77 and 79, or the members 83 and 46, either of which break the magnetic hold on the armature, are, as above stated, essentially a tripping means in that they act only for an instant and control the 45 time of downward flight of the armature. Although they contribute to spring 60 in starting the armature from its cores, they do not continue to act, for the expansion of the spring against the very rapidly diminishing force of magnetic attraction moves the 50 armature much more rapidly than it could be moved by the tripping means and the flanges 77 and 79, or the members 83 and 46, soon separate. Hence, such means are not 55 the means used to obtain high armature speed but rather are used to control the time when the armature-driving means is allowed to act.
- The importance of the tripping means in 60 effecting variations in timing of currents generated will be readily apparent. Such variations are effected simply by turning collar 78, or handle 87 to alter the time at which the flanges 77 and 79 or the members 83 and 46, will engage. No new setting of the eccentric f on its shaft is required. 65
- The closing of the breaker-points and the holding of them closed until the armature is seated, while important and preferred for the reasons outlined, is obviously not concerned in any way with the downward flight of the armature. Even on the upward flight of the armature, the timing of the extra closing and opening may be changed as occasion requires to effect other results. 70
- In conclusion, it may be pointed out that the necessary speed of the armature is really obtained by fully utilizing the factor of the rapidly diminishing force of magnetic pull by the creation and the increase of an air 75 gap. This factor may be termed "magnetic retraction" as distinguished from "magnetic attraction" and is the factor relied upon here to obtain armature speed, as distinguished from the hammer blow or the substantial, 80 and instantaneously applied, initial force heretofore used to produce an initial high speed. Inasmuch as the flux can be held by the choke-coils for an interval sufficient to accelerate the armature to the desired speed, 85 initial speed becomes unnecessary.
- Although the invention has been described herein with considerable particularity in order to make clear to those skilled in the art a preferred means of making use of it, it is 90 to be understood that the invention is not limited to the details illustrated and described except as they are included in the following claims. 95
- What we claim is:
1. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means arranged to act on the armature in opposition to magnetic attraction, and means for diminishing the force of magnetic attraction on the armature to allow the driving means to move the latter. 105
  2. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the 110
  3. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the 115
  4. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the 120
  5. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the 125
  6. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the 130

opposite direction, and relatively slow-acting means for starting the armature from its poles sufficiently to allow the driving means to move the armature, the driving means being then effective to move the armature at rapidly increasing speed due to the rapidly diminishing force of magnetic attraction.

3. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means of less strength than the force of magnetic attraction for moving the armature in the opposite direction, and means for removing the armature from its poles sufficiently to permit the driving means to act due to diminution of the force of magnetic attraction on the armature.

4. In a magneto, of the type wherein an armature moves into and out of engagement with magnetic poles to vary the reluctance of a magnetic circuit and a generating winding is associated with said circuit in which currents are induced by the variation of flux therein; mechanism for moving the armature into engagement with its poles to which it is then held by magnetic attraction, means acting on the armature in opposition to the force of magnetic attraction and exerting a pressure less than said force, means for disengaging the armature from its poles, whereby the force due to magnetic attraction is lessened by the establishment of an air gap and the first-named means is rendered effective to move the armature.

5. In a magneto, of the type wherein an armature moves into and out of engagement with magnetic poles to vary the reluctance of a magnetic circuit and a generating winding is associated with said circuit in which currents are induced by the variation of flux therein; mechanism for seating the armature on its poles to which it is then held by magnetic attraction, driving means arranged to act on the armature in opposition to magnetic attraction, means for diminishing the force of magnetic attraction on the armature to allow the driving means to move the latter, a closed circuit choke-winding associated with the magnetic circuit, and means to open said winding after the armature has moved away from the poles.

6. In a magneto, of the type wherein an armature moves into and out of engagement with magnetic poles to vary the reluctance of a magnetic circuit and a generating winding is associated with said circuit in which currents are induced by the variation of flux therein; mechanism for seating the

armature on its poles to which it is then held by magnetic attraction, driving means arranged to act on the armature in opposition to magnetic attraction, means for diminishing the force of magnetic attraction on the armature to allow the driving means to move the latter, a choke-winding associated with the magnetic circuit and arranged in an electrical circuit which can be opened and closed; and means for closing said circuit as the armature approaches its poles, opening it after the armature is seated on its poles, closing it before the armature leaves its poles and opening it after the armature has moved away from its poles.

7. In a magneto, of the type in which an armature is periodically moved into and held in contact with magnetic poles; driving means arranged to act on the armature oppositely from its supporting force, means for changing the relation of the opposing forces acting on the armature for the purpose of moving the latter away from its poles, and means for varying the time at which said change is effected, said second named means effecting a progressive change in the first instance and creating only a differential of force to start the armature away from its poles.

8. In a magneto, wherein the armature is held by magnetic attraction to its poles, driving means for moving the armature rapidly away from its poles after it has been started therefrom, and means periodically operable to start the armature away from its poles.

9. In a magneto wherein the armature is held to its poles by magnetic attraction, resilient driving means for the armature substantially unstressed when the armature is in contact with its poles and means periodically operable from a moving part of an engine to place the driving means under the desired stress and start the armature in its flight away from the poles by an inelastic transmission of force from said moving part.

10. In a magneto of the type wherein an armature is moved into and out of contact with magnetic poles, resilient means tending to move the armature away from its poles but exerting insufficient force to overcome the force of magnetic attraction between the armature and its poles, and mechanism operable from a moving part of the engine and periodically effective through an inelastic transmission of force from said moving part to overcome the magnetic hold on the armature and permit said resilient means to act.

11. In a magneto of the type wherein an armature is moved into and out of contact with magnetic poles, resilient means tending to move the armature away from its poles but exerting insufficient force to overcome the force of magnetic attraction between the

- armature and its poles, and mechanism operable from a moving part of the engine and periodically effective to first increase the stress in said resilient means and then 5 break the magnetic hold on the armature by an inelastic transmission of force from said moving part.
12. In a magneto, of the type wherein an armature moves into and out of engagement with magnetic poles to vary the reluctance of a magnetic circuit and a generating winding is associated with said circuit in which currents are induced by the variation of flux therein; a reciprocable member slidable relatively to the armature, elastic means through which said member acts on one stroke to move the armature into contact with its poles and by which continued movement of the member on the same stroke 10 is permitted after the armature abuts its poles, and means carried by said member operable at a predetermined point in its return stroke to disengage the armature from its poles.
13. In a magneto, of the type wherein an armature moves into and out of engagement with magnetic poles to vary the reluctance of a magnetic circuit and a generating winding is associated with said circuit in which currents are induced by the variations 15 of flux therein; a reciprocable member slid- able relatively to the armature, elastic means through which said member acts on one stroke to move the armature into contact with its poles and by which continued movement of the member on the same stroke is permitted after the armature abuts its poles, and means carried by said member operable at a predetermined point in its return stroke 20 to disengage the armature from its poles, said means being adjustable to vary the time of departure of the armature from its poles.
14. In a magneto, of the type wherein an armature is moved into and out of contact with magnetic poles, a reciprocable member effective on one stroke to move the armature into contact with its poles and capable of moving on the other stroke without moving the armature, and means on said member effective at a predetermined point in the last named stroke thereof to move the armature away from its poles.
15. In a magneto, of the type wherein an armature is moved into and out of contact with magnetic poles, a reciprocable member capable of pushing but not of pulling the armature and operable on one stroke to push the armature against its poles, and means connected with said member to engage the armature after said member has moved a predetermined distance on its return stroke and apply a pull on the armature.
16. In a magneto, of the type wherein an armature is moved into and out of contact with magnetic poles, a reciprocable member capable of pushing but not of pulling the armature and operable on one stroke to push the armature against its poles, and means adjustably connected with said member to engage the armature after said member has moved a predetermined distance on its return stroke and apply a pull on the armature.
17. In a magneto, of the type wherein an armature is moved into and out of contact with magnetic poles, a reciprocable member slidable through the armature and provided with a shoulder, a spring interposed between said shoulder and the armature, cooperating devices one movable with the armature and the other movable with said member arranged to engage at a predetermined point in one stroke of said member to permit the latter to move the armature in a direction opposite to that in which it is moved through the intermediary of said spring.
18. In a magneto, of the type wherein an armature is moved into and out of contact with magnetic poles, a sleeve fixed to the armature, a lifting member including a portion slidable in the sleeve and having a shoulder, a spring encircling the lifting member and acting between said shoulder and armature to transmit motion in one direction to the latter from the lifting member, cooperating devices one carried by said sleeve and one by said member, and means for reciprocating the lifting member, said devices each having a part arranged in the path of the other and engageable after the lifting member has moved a predetermined distance in the other direction to move the armature.
19. In a magneto, of the type wherein an armature is moved into and out of contact with magnetic poles, a member movable with the armature, a reciprocable member slidable relatively thereto, an abutment provided on the second member by which the other member may be moved in one direction, and an abutment mounted on one of said members to engage the other when the second member is moved in the other direction.
20. In a magneto, wherein the armature is held to its poles by magnetic attraction, resilient driving means for the armature substantially unstressed when the armature is in contact with its poles and means periodically operable to place the driving means under stress and then start the armature from its poles.
21. In a magneto, wherein the armature is held to its poles by magnetic attraction, continuously reciprocable mechanism operable on one stroke to periodically cause the armature to be deposited on its poles, and free to move a predetermined distance on

- its return stroke without moving the armature, substantially inelastic means provided on the armature and said mechanism adapted to engage after said mechanism has moved said predetermined distance and start the armature away from its poles, and means for varying the time in the return stroke at which the armature is started from its poles.
- 16 22. In a magneto, wherein the armature is held to its poles by magnetic attraction, continuously reciprocable mechanism operable on one stroke to periodically cause the armature to be deposited on its poles, and free 15 to move a predetermined distance on its return stroke without moving the armature, substantially inelastic means provided on the armature and said mechanism adapted to engage after said mechanism has moved 20 said predetermined distance and start the armature away from its poles, and means for adjusting said mechanism to vary the time when the armature is started from its poles.
- 25 23. In a magneto, wherein the armature is held to its poles by magnetic attraction, continuously reciprocable mechanism operable on one stroke to periodically cause the armature to be deposited on its poles, and after 30 a predetermined movement on its return stroke to start the armature away from its poles, and means for adjusting said mechanism to vary the time when the armature is started from its poles, said last-named 35 means capable of being varied so that the armature may remain on its poles during reciprocation of said mechanism when desired.
24. In a magneto, of the type wherein an 40 armature is moved into and out of contact with magnetic poles, means to deposit the armature on its poles, resilient means for moving the armature away from its poles and exerting less force on the armature 45 when the latter is in contact with its poles than that due to magnetic attraction, and means operable to increase the stress in said resilient means.
25. In a magneto, of the type wherein an 50 armature is moved into and out of contact with magnetic poles, resilient means for
- moving the armature away from its poles, mechanism movable in one direction to deposit the armature on its poles and diminish the stress on said resilient means so that the armature may be held to its poles by magnetic attraction, said mechanism when moved in the opposite direction arranged to stress said resilient means to the desired degree.
26. In a magneto, of the type wherein an armature is moved into and out of contact with magnetic poles, a reciprocable member effective on one stroke to move the armature into contact with its poles and capable of moving on the return stroke without moving the armature, resilient means for moving the armature on the return stroke, and means movable with said member operable on its return stroke to first place said resilient means under the desired stress and then to detach the armature from its poles to allow the stressed resilient means to move the armature.
27. In a magneto, resilient means for 75 moving the armature away from its poles, an abutment between which and the armature said means is interposed and against which said means acts to move the armature, and means for moving said abutment.
28. In a magneto, resilient means for moving the armature away from its poles, an abutment between which and the armature said means is interposed and against which said means acts to move the armature, and means for moving said abutment in the direction of expansion of said means during 80 said movement of the armature.
29. In a magneto, resilient means periodically expandible to move the armature away 90 from its poles, and mechanism operable during the expansion of the first named means and supplementary to the diminution in the force of magnetic attraction between the armature and its poles to compensate for the natural diminution in stress of said spring.
- In testimony whereof we have affixed our signatures.

PHELPS BROWN.
HAROLD H. CLARK.
